SUCTION CLEANER

Donald G. Smellie, Canton, Ohio, assignor to The
Hoover Company, North Canton, Ohio, a cor-
poration of Ohio

Application December 30, 1933, Serial No. 704,622

11 Claims.

(Cl. 15—16)

The present invention relates to suction cleaners in general, and particularly to new and novel improvements in the construction of the suction cleaner nozzle. More specifically the invention 5 comprises the provision of a suction cleaner nozzle having pile penetrating lips which are tiltably mounted and which are resiliently urged to a normal vertical position.

It is an object of the present invention to provide a new and improved suction cleaner. It is another object of the invention to provide a new and improved suction cleaner nozzle. A still further object of the invention is to provide a suction cleaner nozzle in which the lips are pile penetrating, are pivotally mounted, and are resiliently urged to a normal vertical position. These and other more specific objects will appear upon reading the following specification and claims and upon considering in connection therewith the attached drawing to which they relate.

Referring now to the drawing in which a preferred embodiment of the invention is disclosed:

Figure 1 is a side elevation of a modern suction cleaner embodying the present invention;

Figure 2 is a partial cross-section through the cleaner nozzle showing the lips constructed in accordance with the present invention;

Figure 3 is a bottom view of the nozzle shown in Figure 2;

Figure 4 is a cross section similar to Figure 2, showing a second preferred embodiment of the invention;

Figure 5 is a partial bottom view of the nozzle shown in Figure 4.

Research in the suction cleaner field has disclosed that the provision of nozzle lips which are relatively thin increases the cleaning effectiveness of the cleaner. These nozzle lips are called pile penetrating and are particularly effective in machines relying solely upon air to perform the cleaning function. In the operation of the cleaner, however, pile penetrating lips extend to a relatively great distance into the pile of the covering and increase the force required to move the cleaner. This increase in force required is undesirable. In order to eliminate this undesirable force increase the pile penetrating lips of the cleaner, constructed in accordance with the present invention, are so mounted that they are permitted to tilt, being resiliently urged to a normal vertical position. The tilting action makes easier the sliding action of the lip or lips through the covering, and the force required to move the cleaner is correspondingly decreased.

In the drawing a modern cleaner is shown. The

reference character 1 indicates the cleaner nozzle which is interiorly connected, as in the usual cleaner, to the fan chamber 2 which houses the suction-creating fan 3 driven by an unshown motor positioned within the motor casing 4. The suction-creating fan 3 functions in the operation of the machine to draw cleaning air through the nozzle 1 and exhaust it, with the dirt or foreign matter which is suspended therein, into the dust bag 5 which is removably attached to the exhaust outlet of the fan chamber. The cleaner is movably supported by means of front and rear wheels 6 and 7, there being two of the former which are spaced and which are movable vertically relative to the machine by means of the manual adjusting means 8 for the purpose of raising and lowering the nozzle 1 relative to the surface covering undergoing cleaning. As in the usual cleaner a pivoted handle 23 is provided to the upper end of which the dust bag 5 is attached and supported in the usual manner.

The parts described in the foregoing paragraph comprise the usual suction cleaner and no invention is claimed in their general arrangement or combination except as hereinafter specified.

Referring now to Figures 2 and 3 in particular a cross section through the nozzle 1 discloses the lower end or mouth of the nozzle defined by the front and rear nozzle walls 9 and 10. The mouth is seen to be surrounded by the usual furniture guard 11. The lower edges of the walls 9 and 10 are spaced at a considerable height above the covering undergoing cleaning and the surface-contacting front and rear lips, 12 and 13 respectively, are movably carried by the walls by means of resilient strips 14, 14. These strip members are preferably of rubber and normally hold the lips vertically as shown in Figure 2. The upper ends of the strips are secured to the walls 9 and 10 by rivets 15, 15. The lips extend substantially the entire length of the nozzle.

In the operation of this embodiment of the invention as the machine is moved forwardly over the surface with the suction lifting the surface covering undergoing cleaning into contact with the nozzle lips 12 and 13 these lips penetrate into the covering pile. The frictional force of the covering on the lips flexes the resilient strips 14, 14 and pivots the lips about the line at 50 which the strips are secured to the nozzle, and the lips are tilted rearwardly. When the cleaner is moved in the reverse direction, that is rearwardly, the lips are tilted forwardly. The net result is a decrease in the force required to move 55

the cleaner as the lips slide through the pile of the covering more easily when tilted.

Referring now to Figures 4 and 5 a second preferred embodiment of the invention is disclosed.

- 5 In this embodiment the flexible strips which supported the lips in the first embodiment have been eliminated. Instead lips 12 and 13 are riveted upon shafts 16, 16 which are pivotally carried by the nozzle end walls. Seals 17, 17 enclose the 10 outer sides of the shafts 16, 16 sealing them to the nozzle walls. Removable plate elements 18, 18 of metal are secured to the nozzle walls by means of screws 19, 19 etc., and clamp the elements 17, 17 thereto. The nozzle lips are normally 15 held in their vertical positions by means of spring arms 20, 20 which extend through two pins 21, 21 carried on the inner sides of the lips. Springs 20, 20, of which there may be a pair at each end of the nozzle, are carried by the nozzle end walls 20 on pins 22, 22. The operation of this embodiment of the invention is identical with that first described. The movement of the cleaner over the surface covering in the cleaner operation results in the pivotal movement of the lips resulting in 25 decreased force requirement for movement.

I claim:

- 30 1. In a suction cleaner, a nozzle having a mouth, and a surface-contacting lip tiltably mounted throughout its length and defining one side of the nozzle mouth and movable relative to the nozzle proper by the force exerted by surface covering thereagainst on the movement of said cleaner thereover, and means resiliently urging said lip to a normal vertical position and resiliently opposing movement therefrom.

- 35 2. In a suction cleaner, a nozzle having a mouth, a surface-contacting lip carried by said nozzle defining one side of said mouth, the entire surface-contacting portion of said lip being movable horizontally and relative to said nozzle mouth under the force exerted by a surface covering thereagainst in the movement of said cleaner thereover, and means resiliently opposing movement of said lip relative to said nozzle 40 mouth with a lesser force than the frictional force exerted by the surface covering in the operation of the cleaner.

- 45 3. The construction recited by the preceding claim characterized in that said lip includes a metallic surface-contacting portion which is mounted relative to said nozzle by a resilient flexible strip.

- 50 4. The construction recited by the second preceding claim characterized in that said lip is pivotally mounted relative to said nozzle and is spring-urged to a vertical position.

- 55 5. In a suction cleaner, suction-creating means, a nozzle open to said means and having a mouth, a surface-contacting pile penetrating lip defining a side of said nozzle mouth adapted to extend

into and between adjacent tufts of the pile of a surface covering undergoing cleaning in the operation of the machine, said lip being mounted for tilting movement relative to the nozzle mouth, and means resiliently opposing the movement of said lip from the vertical position with a force less than the pivoting force exerted thereon by the surface covering undergoing cleaning.

6. A suction cleaner including a nozzle and a nozzle lip thereon defining one side of the nozzle mouth, said nozzle lip being pivotally and movably mounted, means resiliently urging said lip to a vertical position, the pivotal axis being so positioned that said lip can assume a multiplicity of angular positions during its contact 15 with a surface covering, said lip being pivotable by a force exerted thereon by a surface covering undergoing cleaning in the movement of said cleaner thereover.

7. The construction recited in the preceding 20 claim characterized in that means are provided to resiliently hold said lip in its vertical position.

8. In a suction cleaner, a nozzle, rigid nozzle lips defining the sides of the nozzle mouth, said lips being pivotally mounted relative to said 25 nozzle and adapted to assume a multiplicity of angular positions relative thereto under a pivoting force exerted thereon by a surface covering slipping thereunder, and resilient means urging said lips to a vertical position.

9. In a suction cleaner, a nozzle having a mouth, a tilttable lip defining a side of said mouth under which cleaning air must pass in entering, said lip being tilttable about an axis above the plane of surface contact under the frictional 35 force exerted by a contacting surface covering in the movement of the nozzle thereover, and means acting to yieldingly resist the tilting of said lip.

10. In a suction cleaner, a nozzle having a mouth, and a tilttable lip defining a side of said mouth under which cleaning air must pass in entering, said lip comprising a surface-contacting portion and a resilient flexible portion connecting and sealing said surface-contacting portion to the wall of the nozzle, said resilient flexible portion being sufficiently flexible to permit of flexing under a frictional force exerted by a surface covering undergoing cleaning against said surface-contacting portion.

11. In a suction cleaner, a nozzle having a mouth, a pivoted nozzle lip defining a side of said mouth under which cleaning air must pass in entering, said lip being pivoted to said nozzle about an axis above the plane of surface of said lip, means sealing said lip to an adjacent wall of said nozzle, and spring means to oppose tilting of said lip under a frictional force exerted by a surface covering undergoing cleaning.
